UNITED STATES PATENT OFFICE.

JAMES L. PAXTON, OF OMAHA, NEBRASKA.

PACKING.

1,181,084.

Specification of Letters Patent. Patented Apr. 25, 1916.

Application filed May 29, 1913. Serial No. 770,670.

To all whom it may concern:

Be it known that I, JAMES L. PAXTON, a citizen of the United States, residing at Omaha, in the county of Douglas and State 5 of Nebraska, have invented certain new and useful Improvements in Packing; and I do hereby declare the following to be a full, clear, and exact description of the invention, such as will enable others skilled in the art 10 to which it appertains to make and use the same.

This invention relates to improvements in metallic packing of the type adapted for effecting close joints between moving parts, 15 and the objects in view is the improvement of the specific type of packing set forth in U. S. Letters Patent No. 647,313, granted to Thomas W. Mitchell, under date of April 10, 1900.

20 In the accompanying drawing, Figure 1 is a view in elevation of a packing embodying the features of the invention, the piston being illustrated in section. Fig. 2 is a central cross section therethrough.

25 While the structure set forth in the above-named patent have proved exceptionally efficient, some difficulty has been experienced from the tendency of the springs to creep longitudinally until they wedge in between 30 the rocking ends of the packing segments and the retainer ring, which occurs usually after the segments have become somewhat worn. Obviously, the end of a spring wedged between the rocking end of one of 35 the segments and the retaining ring will interfere with the rocking movement and thus prevent the segment from maintaining an intimate contact with the piston.

The present invention is designed to over- 40 come this difficulty and effectively attains this object through the embodiment illustrated in the accompanying drawing in which 1, 1 indicate the segments of the packing ring, said ring surrounding the piston 45 2.

Each segment 1 has each end beveled, one end of one segment overlapping the contiguous end of the other segment, the opposite end of the first segment underlapping the opposite end of the second segment. The 50 bevel of the ends of the segments 1 is incident to the curvature of said segments so that said ends are relatively flat with the flat faces extending substantially tangentially with respect to the inner curvature of 55 the segments and to the surface of the piston 2, the planes of said flat ends being

parallel. Thus the segments are adapted as the material thereof wears away to be moved radially toward the piston and thus maintain an intimate contact therewith. To 60 insure such radial movement, as well as to provide for a constant pressure maintaining the segments in contact with the surface of the piston 2, each segment 1 is engaged by a plate spring 3. The springs and segments 65 are surrounded by the retainer ring 4, and each segment is formed with a longitudinal peripheral notch 5, which accommodates the respective spring 3 and at the ends of which the respective segment is formed with shoulders 6, 6, which are sufficiently abrupt to insure contact therewith by the respective end of the corresponding spring 3, when the spring creeps longitudinally, so that the spring cannot possibly escape and wedge 70 itself between the respective end portion of the segment and the ring 4. To insure this result, each spring 3 has its end portions bent inwardly, as at 7, 7. Each spring 3, preferably centrally thereof, is formed with 80 a radially, inwardly extending projection 8, which is preferably formed of the material of the spring stamped or punched to produce said projection. The projection serves as the single point of contact between the 85 spring and the respective segment 1, the end portions of the spring bearing against the retainer ring under spring pressure tending to move outwardly, and a resultant spring pressure at the projection 8 being exerted 90 radially inwardly.

Each end portion of each segment 1 has its outer surface rounded, as indicated at 9, and the rounded portion extends to the respective shoulder 6, so that each of the seg- 95 ments is free to rock when necessary for effecting the requisite inward travel, and liability of interference with such rocking by the springs 3 is entirely obviated. It will thus be noted that the two segmental 100 sections 1 constantly coöperate to form a very intimate joint about the piston, and that the single point contact 8 of each spring both obviates undue friction and leaves the respective section 1 free for such movement 105 as variations in wear may necessitate.

What I claim is:—

1. In a piston packing, a packing ring comprising arcuate sections, each having a bevel at one end with the inclined face of 110 the bevel exposed outward and a correspond- ing bevel at the other end with the inclined

face of the bevel exposed inward, each beveled surface lying substantially at a tangent to the circle described by the inner surface of the ring, and the inwardly exposed inclined face of each section overlying the outwardly exposed inclined face of the other, a spring for each section pressing the middle portion inward, and means for preventing movement of each spring to a position 10 pressing an end portion of its respective section.

2. In a piston packing, a packing ring comprising arcuate sections, each having a bevel at one end with the inclined face of 15 the bevel exposed outward and a corresponding bevel at the other end with the inclined face of the bevel exposed inward, each beveled surface lying substantially at a tangent to the circle described by the inner surface 20 of the ring, and the inwardly exposed inclined face of each section overlying the outwardly exposed inclined face of the other, and a spring for each section pressing the middle portion inward, each section having 25 a shouldered portion adjacent each end of the spring for confining the spring against substantial displacement.

3. In a piston packing, a packing ring comprising arcuate sections, each having a bevel at one end with the inclined face of the bevel exposed outward and a corresponding bevel at the other end with the inclined face of the bevel exposed inward, each beveled 30 surface lying substantially at a tangent to the circle described by the inner surface of the ring, and the inwardly exposed inclined 35

face of each section overlying the outwardly exposed inclined face of the other, and a plate spring for each section pressing the middle portion inward, each spring having 40 at its middle portion a projection extending toward and engaging the respective section, and each section having extensions at its end portions disposed to interrupt longitudinal travel of the spring.

4. In a piston packing, a packing ring section adapted to coöperate with a like section and having a bevel at one end with the inclined face of the bevel exposed outward and a corresponding bevel at the other end with 45 the inclined face of the bevel exposed inward, each bevel surface lying substantially at a tangent to the circle whose arc is described by the inner surface of the section, and the inwardly exposed inclined face of 50 the section being adapted to overlie the outwardly exposed inclined face of a coöperating section and to have its outwardly exposed inclined face overlapped by the inwardly exposed inclined face of a coöperating 55 section, the section being formed with terminal shoulders and a peripheral recess between the shoulders adapted to accommodate a spring confined against circumferential travel by the shoulders.

65 In testimony whereof I affix my signature in presence of two witnesses.

JAMES L. PAXTON.
